James Alwater
Letter Patent

The Schedule referred to in these Letters Patent and, making part of the same containing, a description in the words of the said James Alwater himself of his improvement in the common fire Grate.

To all people to whom these presents shall come greeting,
Know ye that I James Alwater of New Haven in the County of New Haven State of Connecticut a Citizen of the United States have invented constructed & applied to use a new & useful improvement upon my patent Improvement in the common fire Grate which new & useful improvement I describe & specify in manner following (viz.) This improvement consists in making alterations in my patent improvement in the common fire grate, for which I have obtained Letters Patent from the Government of the United States dated the 25th day of October one thousand eight hundred and thirty two & which is particularly described & set forth in the Specification to said Letters Patent annexed and making part of the same as the same are on record in the office of the Secretary of State of the United States according to the act of Congress in such case provided to which Letters Patent & Specification on record as aforesaid, express reference is hereby made, for a full description of said instrument or manufacture to which this present improvement is made by way of alteration or addition & which new & useful improvement addition or alteration for which this patent is solicited I further describe & specify as following Construct my patent so formed common fire Grate according to my said Specification in every respect except the following (that is to say instead of the bars or bars slide plates. balanced by weight & used to enlarge or diminish or alter or close the openings which make the channels or flues of the patent improved fire grate aforesaid & which are placed at the back thereof to make the back of the grate of solid materials such as soap stone

P

225.

in fire brick a fire with one or more openings in that part of the back which usually incloses the fuel which openings should slope upward & outwards from the inside of the grate toward the chimney in the rear at about an angle of forty five degrees measured from the plane of the back of the grate & these openings should in their size correspond with and be proportioned to the size of the whole grate but should not in ordinary grates vary much from two inches in width & should be somewhat shorter than the width of the back of the grate measured from side to side & not more than three such openings will ordinarily be needed or found useful. And in order to regulate the draught of the grate at pleasure so as to extinguish the fire or cause it to burn with greater or less intensity, construct a valve or moveable cover or stopper for each of the openings of some solid material which will bear a high degree of heat such as iron or some other metal & large enough fully to cover the opening or orifice to which it is to be applied, which valve, cover or stopper should be attached firmly to a rod or shaft supported by proper bearing at or near each end thereof, which bearings may be placed in the back or sides of the grate so that the rod or shaft & the valve cover or stopper attached thereto will readily turn together & thus the valve cover or stopper will open or close the openings or draughts already mentioned in the back part of the grate separately or together at pleasure. The rod or shaft must be of solid materials such as will bear a good degree of heat such as iron or some other hard metal. Each rod or shaft & the valve, cover or stopper, attached to it may be turned by any means that are convenient. A useful mode of doing it will be to form a small or rank at one end of each rod or shaft & attach one end of a wire or small rod to the rank at the end of each rod or shaft before described & bring the other end to the front part of the grate & place a knot or other convenient handle to this other end so that when the valve cover or stopper closes its corresponding opening by its own weight then by pulling the wire or small rod each shaft or rod with its valve cover or stopper will be made to revolve & open the place, orifice or opening to which it is fitted, or when more convenient a knot or handle may be placed

Jan. 9, 1833

placed at one end of each rod or shaft to which the valve cover or stopper is attached & by this the same thing may be accomplished. One end of the cover or small rod when such is used, is made to project from the bearing, & a small notch is made in the wire or small rod which a part thereof that when the opening is unlased by pulling forward the wire or small rod the notch may fall upon the bearing's hole so the valve cover or stopper firmly in its position. And if the knob or handle be placed at the end of the rod or shaft, then a small hole is made near the bearing of that end of the rod or shaft & a pin is placed as to extend from the knob or handle toward the bearing & when the rod or shaft with its valve cover or stopper fast in its position when that may be according as it is more or less turned. The drawings hereto annexed & herein referred to & which make a part of this specification I describe as follows. Figure 1 is a front view of a patent improved common fire grate with new improvements in this instrument set forth, made with three openings in the back marked a, b, c. & three knobs d, e, f, represented in their positions when the openings a, b, c. are not closed. when the openings a, b, c. are closed the knobs will be in the positions g, h, i. The residue of the figure represents two side chambers or air cells A, B, in use to the grate instead of pipes for the purpose of diffusing heat to the surrounding air & other objects with two doors C, D for the purpose of removing ash or dirt of any party or of dispensing the draught of the grate. Figure 2. exhibits the rods or shafts a, b, c. with the valve, cover or stoppers d, e, f, in various positions & the knobs g, h, i. Figure 3. shows the small rods or wires g, h, i. with the knobs j, k, l. at the ends & the notches m, n, o, on the small rods or wires & these are represented in positions corresponding with the positions of the valve covers or stoppers as seen in Figure 2. Figure 4. shows the interior of the side chambers or air cells which by means of the openings a, b, c, & cause the hot air to diffuse ~~the~~

220.

cover'd at the opening a, which is connected with the chamber in the grate as seen in Figure 1. If the top air passes over the partition a & downwards under the partition b, & then upwards over the partition c, & then downwards & under the partition d, it is off into the pipe f, which is to be connected with a flue & carry off the smoke & air. Figure 5 is a front view of an improved fire grate with a double set of openings a, b, c, d, e, f, placed in the sides of the grate & none at the back with two chambers, g, h, at the sides of the grate for each of the sets of openings there air cells or chambers i, k, as little different in shape & without internal divisions receiving the hot air & smoke at aa, bb, & passing it off at cc, dd, & two doors in the same b, m, n, Figure 6 is an interior or front view of one side of this grate with its openings a, b, c, and the knobs d, e, f. Figure 7 is a back view of one side of this grate as it would be seen if its chamber was removed with the rods or shovels a, b, c, valves cover'd or stopp'd d, e, f, & knobs g, h, i, in various positions. Figure 8 is a front view of an improved fire grate which differs from the grate represented in Figure 1, by the addition of an air or a, at the top & a pan & fender b, at the bottom & three slightly cover'd doors c, d, e, in front to close up the whole grate. The door c & e, may be made of sheet iron or tin or such like material. The door d, is made of a frame of brass or polished iron or steel semi-cylindrical bars made flat in the back side & a lining or frame of tin or sheet iron made fast to the frame of the door which lining is perforated with the holes f, g, & h, which holes are filled with iron loops to admit of the fire being seen while the air is excluded from passing. The pilasters h, i, j, k, with the iron l, m, n, o, are added for ornament. Figure 9. is a view of the same grate with the doors c & d, as seen in Figure 8, removed in order to show the front of the grate formed of iron lattice work a, a, and made flat or straight from side to side of the grate so that the curve of the door Figure 8. d, will keep the said door off from the front of the grate a, a, & so prevent the bars of the door d, Figure 8, from being so much tarnished by the heat. The lower door b, is made double curv'd in front

231

afft in the case as exhibited at the top of the same at a, a, & at the bottom is placed a slide or stopper c, which when pushed back also leaves the space between the front & back of the door at the bottom when fully forced opens the same. The use of this is to admit the air which is to feed the fire to pass upward thro' the door & out at the top between the front & back plates of the door at c, & then pass thro' the fuel to ignite the same. The part f is seen in this figure which is held by the fender b, in Figure 8. The grate in Figure 5, is represented with a top w. & in Figure 8, with a top w' the grate in Figure 1 may also be used with a top w' in Figure 5 & w in Figure 1 with a few or bottom when needed. These drawings exhibit the patent improved common fire grate as altered & claimed in this patent in some of the various positions on which the same may be conveniently used according to the fancy or taste of the owner as also to correspond with the furniture of the apartment on which they are placed. In Figure q, or q', is seen a piece of sheet iron or other solid substance which in shape is a segment of a circle & is used to prevent the air which comes in from below thro' the door b, otherwise from ascending any higher than this part of the grate & causes the air to pass thro' the fuel as before mentioned. (whether door c, as seen in Fig. 8 is closed or not) The grate is filled with fuel. I claim as my improvement that in the place of a slide or stopper or grate used in my patent improved common fire grate to regulate the draught of the same, I have substituted as many valves cover or stoppers as there may be openings in the back or sides of the grate by means of which the draught is regulated at pleasure or entirely closed in the manner set forth in this specification & all the parts which are set forth in my patent for my improved common fire grate on the 25th October 1832, according to the law of Mass or grates are hereby claimed in a more convenient manner and this is all I claim in this patent. In testimony that the above is a true specification of my said improvement as above described I have hereunto set my hand the 17th day of December one thousand eight hundred
